TUBE-PUSHING BENCH

Heinrich Heetkamp, Dusseldorf, Germany, assignor to Demag Aktiengesellschaft, Duisburg, Germany

Application March 5, 1936, Serial No. 67,309
In Germany March 7, 1935

4 Claims. (Cl. 205—4)

In order to ensure the smooth working of tube draw benches operating at a high speed, it is advisable to provide guides not only in front of the bed of rings or reducing dies but also in the bed 5 between the rings or reducing dies. Hitherto for this purpose guide rings inserted between the reducing dies have been employed, but according to recent proposals guides have been provided in which the guiding elements are disposed radially 10 in such manner as to be adjustable relatively to each other and are resilient, while at the same time they are forced into the operative position by means of a suitable pressure medium. Guide rings have the disadvantage that only the mandrel with the bloom and not the push rods which 15 require to be prevented from bending are directly enclosed and supported, so that thus undesirable bending of the mandrel push-rods is possible. The guiding devices of the kind hereinbefore described 20 avoid these disadvantages, but on the other hand they have the disadvantage of being complicated in construction, and giving trouble by reason of the resilience provided, having regard to the fact that the forces occurring are uncontrollable in 25 their intensity.

To avoid these disadvantages, according to the invention the rigid closed guides hereinbefore referred to are employed, and the disadvantage of the open guide is avoided by the fact that the 30 guides can be skewed for the purpose of changing the effective cross-sectional shape of the passage through them. The rocking axis of the guides will advantageously intersect the drawing axis, although as will be obvious the non-coincidence 35 of the skewing axis with the drawing axis is unimportant. It is advisable to form the hole in the closed guides which forms the mandrel guide, as a regular polygon, but more particularly a hexagon, so that the mandrel or push-rod is effectively supported at diametrically opposite 40 positions.

The invention is diagrammatically illustrated in the accompanying drawing, by way of example.

Figures 1 to 3 illustrate the construction of apparatus according to the invention in longitudinal section, in front elevation and in side elevation respectively.

Figure 4 shows the method by which the guide member according to the invention is fitted in the draw bed.

Figures 5 and 6 illustrate a possible construction of the device for adjusting the guide and

Figure 7 shows diagrammatically a disposition of the skewing axis for the guide member other than that illustrated in Figures 1 to 6.

Referring to the drawing, 1 denotes the closed guide member. The hole in each guide member 1 which forms the actual guide is hexagonal in shape, as shown in Figures 2 and 3, and thus the mandrel push-rod is controlled at four diametrically opposite points when the guide is skewed, while when the guide is disposed normally the work upon the mandrel may be supported at six points. As Figure 4 shows, the members 1 are fitted to the draw bed 2 in such 10 manner that they can be rotated around their respective axes A—A. In Figure 1 the guide member 1 is disposed at right angles to the mandrel 3 and to the tubular body 4 surrounding the mandrel (cf. the guide member in the uppermost 15 position of Figure 4). In this position of the guide members 1 the latter provide free passage for the mandrel and the blank. In order that the mandrel freed of the blank or the push-rod may be firmly guided in the draw bed, the guide members 1 are skewed by partial rotation around the corresponding axis A—A. As will be seen by reference to Figures 2 and 3, oppositely disposed edges of the hexagonal hole in the guide member 1 respectively at the front and rear faces bear 25 against the mandrel or push-rod at 5, so that the latter cannot be deflected from its axial position or be bent. In Figure 4 three guide members 1 are shown skewed into the guiding position.

For the purpose of skewing the guide members a wedge in conjunction with a spring can be employed, as shown by way of example in Figures 5 and 6. According to these constructions the guide member 1 is mounted in the frame 6 so as to be capable of skewing around the axis A—A, the stop 7—which may be a screw—limiting the amount of deflection. The frame 6 is inset into the draw bed. The spring 8 tends to maintain the guide member 1 in the position of rest shown in Figure 1 and in the uppermost position of Figure 4. The guide member 1 is adapted to be forced into the skewed position by the use of a wedge 9 acting in conjunction with a projection 10 on the guide member 1. The wedge 9 is advanced by mechanism for the purpose provided in the casing 11; this causes the guide member 1 to skew as shown in Figures 2 and 3.

Figure 7 illustrates a possible alternative arrangement in which the skewing axis for the 50 guide member 1 is disposed away from the axis of the mandrel.

The invention is not limited to a particular form of the hole in the guide member 1 which constitutes the guide member. It is advantageous 55

however to form the hole as a regular polygon as shown in the drawing.

I claim:

1. Tube draw benches provided with closed rigid guide members disposed in fixed position in the draw bed, and whose guide passages are larger than the diameter of the mandrel and which guide members by skewing during the forward thrusting movement of the mandrel apply their oppositely disposed edges against the mandrel to form fixed guiding passageways therefor.
2. In tube draw benches, a rigid closed guide member for the mandrel and mandrel push-rod and means for skewing the guide member in relation to the drawing axis of the bench, the said

guide member having a passageway which in the position of the guide member normal to the drawing axis is of an area to afford free passage to the mandrel and the work thereon and in the skewed position of the guide member presents an effective cross-sectional area for the guidance of the mandrel and mandrel push rod.

3. In tube draw benches, according to claim 2, the provision of a passageway in the guide member of the form of a regular polygon.

4. In tube draw benches according to claim 2, the provision of a passageway in the guide member of the form of a hexagon.

HEINRICH HEETKAMP. 15
